(57) **CLAIM**

The ornamental design for a graphic rail system, as shown and described.

DESCRIPTION

FIG. 1 is a view in perspective of a graphic rail system, with the broken line showing for illustrative purposes only and forming no part of the claimed design;

FIG. 2 is a top view of the graphic rail system of FIG. 1.

FIG. 3 is a bottom view of the graphic rail system of FIG. 1.

FIG. 4 is a rear view of the graphic rail system of FIG. 1.

FIG. 5 is a front view of the graphic rail system of FIG. 1; and,

FIG. 6 is a side view of the graphic rail system of FIG. 1.
